United States Patent Office.

ISAAC GOODSPEED, OF NORWICH, CONNECTICUT.

Letters Patent No. 60,878, dated January 1, 1867.

IMPROVEMENT IN FILE-CUTTING MACHINES.

The Schedule referred to in these Letters Patent and making part of the same.

TO ALL WHOM IT MAY CONCERN:

Be it known that I, ISAAC GOODSPREAD, of Norwich, in the county of New London, and State of Connecticut, have invented a new and improved Machine for Cutting Files; and I do hereby declare that the following is a full, clear, and exact description thereof, which will enable others skilled in the art to make and use the same, reference being had to the accompanying drawings, forming part of this specification, in which—

Figure 1 is a side sectional view of my invention taken in the line $x x$, fig. 3.

Figure 2 is a transverse vertical section of the same taken in the line $y y$, fig. 1.

Figure 3 is a plan or top view of the same.

Similar letters of reference indicate like parts.

This invention relates to a new and improved machine for cutting files, and has for its object simplicity of construction, and the obtaining of all the advantages attending the more expensive and pretentious machines hitherto devised for the purpose.

A represents the base or bed-plate of the machine, on which two standards, B B, are secured to support the driving shaft C, which may be rotated by any convenient power. On one end of this driving shaft, C, there is attached a crank-pulley, D, having two arms, E F, connected to it by one and the same pin, a, (see figs. 1 and 3.) G G are two uprights, also secured to the base or bed-plate A, and having a hammer, H, suspended between their upper ends on pivots or a shaft, b; which are at the upper end of the hammer, so as to admit of the latter having a swinging action or motion, as will be fully understood by reference to fig. 1. The hammer H, at its upper edge, has a notch, c, made in it to receive a hook, d, at the outer end of the arm E, and the swinging motion is given the hammer by said arm as it is operated by the crank-pulley D, the hook d catching into the notch c at the termination of the forward movement of E, and as E is drawn back the hammer is raised until the hook is drawn out of the notch, when the hammer descends with a force due to its gravity, and gives the blow to the cutter-stock I. The force of the blow of this hammer may be varied or modified as occasion may require by means of a spring, J, attached to the under side of the hammer, the free or disengaged end of said spring, as the hammer about reaches the termination of its downward movement, coming in contact with a set-screw, K, which passes through a cross-bar, e, secured to the upper parts of the uprights G G. It will of course be seen that, by adjusting the screw K, the force of the blow of the hammer may be regulated as desired. The cutter-stock I, is arranged and operated in a peculiar manner, as follows: It is provided with a longitudinal slot, f, which extends from its bottom or lower edge nearly to its top, and said cutter-stock is fitted on a fixed shaft, L, the ends of which pass into the uprights G G, the shaft L passing loosely through slot f, so that the cutter-stock may rise and fall, and turn freely thereon. M represents the cutter, which is fitted in a slot, g, made in the stock I, parallel with the slot f, and secured therein by set-screws, h. The cutter M is fitted obliquely in the stock I, so as to make an oblique and diagonal cut in the file blank, (see fig. 1,) and to the front and rear sides of the stock I there are attached respectively springs, N N', the use of which will presently be shown. The upper edge of the arm F is of curved form, as shown at i in fig. 1, and the outer part of said arm rests and works upon a cross-bar, j, attached to the lower parts of the uprights G G by screws, k, which pass through vertical oblong slots, l, in the cross-bar, into the uprights, and admit of the cross-bar j being adjusted higher or lower, as may be desired. The arm F has two oblong slots, m m, made longitudinally through it, in which pins, O O', are secured by screws, n, the oblong slots admitting of the adjustment of the pins nearer to or further from each other, as may be desired. From one side of the cutter-stock I a pin, o, projects, underneath which the arm F works; and P is a taper screw, which passes horizontally through one of the uprights, G, and enters the slot f in the cutter-stock I, (see fig. 2.) Q is a sliding bed, which is fitted and works between parallel guides, p p, attached to the upper surface of the base or bed-plate A; and R is a spring clamp or pressure plate, the ends of which are fitted on screws, q q, in the base or bed-plate A. This spring clamp or pressure plate bears upon the file blank S on the bed Q, and the shank end of the blank S is fitted under a spring, T, at one end of the bed Q. The spring T and clamp or pressure plate R hold the blank in proper position on the bed Q, and the pressure of the plate R on the blank S may be regulated as desired by adjusting the screws q q.

The operation is as follows: The file blank S is properly secured on the sliding bed Q by means of the spring T and pressure plate R, as described, the end of the blank near the shank being under the pressure

plate R. Each time the arm F is moved forward under the revolutions of the crank-pulley D, the curved upper edge, *i*, of said arm acts against the pin *o*, raises the cutter-stock I, while the pin O of the arm F comes in contact with the spring N', and shoves outward the cutter-stock. By these means the cutter M is raised from the blank S, and moved outward so as to descend upon the blank for a succeeding cut, the hammer H falling upon the cutter-stock when the cutter M reaches the blank. Directly after the hammer H falls upon the cutter-stock, and a cut is given the blank S, the pin O' presses against the spring N, the arm F being drawn back, and the blank and bed Q are moved in the direction indicated by arrow 1. This constitutes the feed movement; the cutter M itself being used as a medium to feed the blank along. At the termination of this feed movement, the cutter M is raised and shoved outward for a succeeding cut, as previously described. The length of the feed movement is regulated by adjusting the pin O' in its slot, *m*, and the length of the outward movement of the cutter M by adjusting the screw P, screwing the same a greater or less distance into the slot *f*, the taper form of the screw regulating the swinging movement of the cutter-stock. In order to give the reverse or cross oblique cut to the file blank, I insert another cutter-stock in the machine, having its slot, *g*, made in a reverse oblique position to the other.

It will be seen from the above description that the machine is composed of but few parts, is very simple in construction, and may be manufactured at a reasonable cost.

Having thus described my invention, what I claim as new, and desire to secure by Letters Patent, is—

1. the swinging hammer H, operated through the medium of the arm E and crank-pulley D, in combination with the cutter-stock I, substantially as and for the purpose set forth.
2. The arm F, provided with the pins O O' and the upper curved edge *i*, in combination with the cutter-stock I, provided with the springs N N', the pin *o*, and slot *f* to receive the shaft I, on which the cutter-stock works, substantially as and for the purpose set forth.
3. The taper screw P, in combination with the slotted cutter-stock I, substantially as and for the purpose specified.
4. The spring T, attached to the sliding bed Q, in combination with the spring clamp or pressure plate R, attached to the base A by the screws *q q*, substantially as and for the purpose set forth.

ISAAC GOODSPEED.
